C. SPIRO.

MARGIN GAGE DEVICE.

APPLICATION FILED APR. 28, 1919.

1,398,282.

Patented Nov. 29, 1921.

UNITED STATES PATENT OFFICE.

CHARLES SPIRO, OF NEW YORK, N. Y.

MARGIN-GAGE DEVICE.

1,398,282.

Specification of Letters Patent. Patented Nov. 29, 1921.

Application filed April 28, 1919. Serial No. 293,070.

To all whom it may concern:

Be it known that I, CHARLES SPIRO, citizen of the United States, residing at New York, in the county of New York and State 5 of New York, have invented certain new and useful Improvements in Margin-Gage Devices, of which the following is a specification.

This invention relates to margin gage 10 devices and particularly to the construction of the right and left hand margin controlling stops of a typewriting machine.

The invention has for an object to provide a novel and improved construction of margin gages freely slideable upon a typewriter carriage and adapted to be locked in position by means upon a relatively fixed part, together with means for releasing said gages when it is desired to write beyond the established margin.

A further object of the invention is to provide an improved structure of margin stop slideably mounted upon a toothed bar and having means to engage and move a stop 25 pawl into locking engagement with the teeth of said bar.

Another object of the invention is to present a novel construction of right margin gage freely slideable upon a toothed bar and 30 having a pivoted member adapted to engage the teeth of said bar when engaged by a co-operating part, such as a bell ringer or line lock lever.

Other and further objects and advantages 35 of the invention will be hereinafter set forth and the novel features thereof defined by the appended claims.

In the drawing—

Figure 1 is a front elevation of the invention;

Fig. 2 is a section on line 2—2 of Fig. 1 with the sector and typebar in position;

Fig. 3 is a vertical section on line 3—3 of Fig. 1;

Fig. 4 is a detail section on line 4—4 of Fig. 3;

Fig. 5 is a perspective of the right hand margin gage, and

Fig. 6 is a detail section on line 6—6 of Fig. 1.

Like numerals refer to like parts in the several figures of the drawing.

The numeral 10 designates a base plate for the carriage frame 11 which may be 55 of any desired construction, and this plate can be mounted upon the frame of a type-

writing machine in any preferred manner. The frame 11 carries at the rear a guide rod 12 upon which the carriage 13 is slidably mounted, for instance by a sleeve 14. The 60 front of the carriage is supported by a truck or carrier wheel 15 which travels upon a rod 16 pivotally mounted at its opposite ends in the frame 11. The carriage 13 is provided with a fixed gage bar 17 having at 65 one end the holding teeth 18 upon its under face and formed at its opposite end with holding teeth 19 upon its upper face.

The margin gage 20 is freely slideable upon the bar 17 and disposed to establish a margin 70 at the left hand end of the platen 21 which is rotatably mounted in the carriage 13 in the usual manner. If desired this gage may support a paper guiding finger 22 extending upward at the front of the platen and carrying a bearing roller 23. The gage is adjustably held in position by a spring 24 secured thereto and frictionally bearing upon the bar 17. This gage is also provided with a depending angularly disposed lip or toe 25 80 mounted to coöperate with a stop pawl 26.

This pawl is pivotally mounted at 27 upon the rod 16 and formed beneath its pivot with a holding face 28 disposed to contact with a restoring spring 29 carried by an extension 30 from the pivoted rod 16. In the travel of the carriage when the lip 25 engages the tooth 31 of the pawl 26 it is lifted into locking engagement with one of the teeth 18 upon the bar 17. If it be desired 90 to release this margin stop in order to write beyond the left margin on the paper, the pawl may be moved out of engagement with the tooth by rocking the rod 16. For this purpose any preferred means may be provided, for instance, a depending lever 32 secured to one end of the rod, and the latter also be provided with a restoring spring 33 secured thereto and to the carriage frame, as shown in Fig. 1. When the pawl is so 100 rocked away from the gage bar the spring 29 restores it to lowered position and also permits the lip to ride over the tooth thereof in the return travel of the carriage.

The right hand margin gage is constructed to coöperate with the bell ringer and line lock and comprises a slide casing 35 mounted to freely move on the gage bar 17 and it may be provided with a paper finger 36 carrying a feed roller 37 and similar in construction to the finger 22 before described. Upon this casing a pawl 38 is

pivoted at 39 and the oppositely extending arms 40 thereof are each provided with a holding tooth 41 adapted to seat in the teeth 19 upon the upper face of the bar 17. These 5 arms are normally held in a horizontal plane and in disengaged position by a spring 42 secured to the casing and bearing upon the upper face of the arms. The lower portion or toe 43 of this pawl is disposed to success- 10 sively engage and operate a bell ringer lever 44 and a line lock lever 45. This toe 43 is formed with an angularly disposed inclined face 46 at one side which acts to cam away or move these levers out of its path in the 15 return travel of the carriage.

Any preferred form of bell ringing mechanism may be used, and a desirable construction is herein shown in which the lever 44 is pivoted at 47 upon a bracket 48 depending from the base plate 10 and provided with a lifting lug 49 extending beneath the hammer arm 50 which is mounted upon the pivot 47. The lever 44 is restored to normal position by a spring 51 extending from a lug 52 25 thereon to the base plate. The free end of this lever is also formed with a curved face 53 to engage the toe 43 which rocks the lever in the return travel of the carriage. The arm 50 is provided with the hammer 54 to 30 contact with a bell 55 and is restored to initial position by a spring 56 extending therefrom to a projection 57 from the bracket 48.

Any ordinary character of line locking mechanism may be used, but a preferred 35 form is herein illustrated in which the lever 45 is pivotally mounted at 58 upon the locking lever 59 and has its lower end formed with a notched tooth 60 disposed to embrace a plate 61 carried by a bracket 62 extended 40 from a universal bail 63. This bail is mounted on the sector 64 in the usual manner and actuated in a rearward reciprocating movement by a shoulder 65 upon a type bar 66, as shown in Fig. 2.

45 The locking lever 59 is pivoted at 67 upon the sector and normally held in contact with a stop 68 thereon by a spring 69 secured at one end to the sector and at its opposite end to said lever. The contact lever 45 is adapt- 50 ed to yield outwardly when engaged by the toe 43 in the return travel of the carriage and is restored to vertical position by a spring 70 disposed between the contact and locking levers, and such restoring movement 55 is limited by a stop 71 below the pivot of the contact lever, as shown in Figs. 2 and 3. If it be desired to write beyond the right hand margin, as in the addition of letters to complete a word, the contact lever 45 may 60 be moved out of engagement with the toe of the pawl 38 by the tail 72 formed on the stop pawl 26 and disposed at the rear of the contact lever. This action is effected by 65 rocking the rod 16 which releases both margin gages and the line locking lever is with-

drawn from the bail by its restoring spring so that all parts are left free for further writing.

The operation of the invention will be apparent from the foregoing description and it will be seen that both margin gages are freely movable upon the gage bar and are automatically locked in engagement therewith when brought into contact with a co-operating part. The left hand gage or stop 70 forces the stop pawl into a tooth upon the bar and this pawl being mounted upon the rocking release rod also controls the release of the line locking mechanism through its tail disposed to engage a member thereof. 75 Both of the margin stops are freely movable upon the gage bar and may be readily slid into the desired position to establish the margins. When starting a line the carriage is moved toward the right until the left hand 80 gage lifts the stop pawl into engagement with the toothed bar which locks the gage in position to form a stop. If it be desired to write to the left of this margin, as when making marginal notes, a backward pressure 85 upon the handle of the rocking rod shifts the stop pawl out of engagement with the bar and leaves the carriage free for further travel toward the right. As soon as this pressure is relieved the parts are automatically restored to initial position and in the 90 carriage travel toward the left the pawl will yield to permit the lip of the gage to ride over the same. As the writing approaches the right hand side of the sheet the margin 95 gage at that point operates the bell ringing lever and its engagement therewith rocks the pawl carried upon the gage so that one of its arms engages the teeth upon the upper face of the gage bar. The continued travel 100 of the right hand gage causes it to operate the line lock lever and the contact with either face of the depending arm of the pawl locks the gage to form a stop. When it is desired 105 to write beyond the right margin the rock shaft is operated to bring the tail of the stop pawl into contact with the contact lever of the line lock and shift the same out of engagement with the pawl upon the right hand gage. Such action releases the line lock and 110 the stops leaving the carriage free to be moved in either direction. When the pawl upon the right hand gage has moved to the left of the contact lever of the line lock and the carriage is to be restored to initial position, the inclined face of this pawl moves the lever out of its path without affecting the line locking lever which is released from the universal bail by its restoring spring 115 when out of engagement with the gage pawl. 120 The curved face of the bell ringer lever contacting with the incline upon the pawl permits the former to be depressed without acting upon the bell hammer. The control and release of both of the margin gages, as well 125 130

as the line lock mechanism, is effected by the single rock shaft so that the several devices are disposed in coöperative relation to perform their functions.

- 5 The invention presents a simple, efficient and economically manufactured construction of margin gage devices, and while the specific construction has been shown and described, still changes and alterations may be
10 made therein as the invention is not confined to such details as set forth in the following claims.

What I claim is—

- 1 In a typewriter, a carriage provided
15 with a platen, a gage bar mounted upon said carriage, a margin gage freely slideable on
· said bar, means to secure said gage upon
the bar, and means upon a relatively fixed
part to control said securing means for re-
20 taining or releasing said gage.

- 2 In a typewriter, a carriage provided
with a platen, a gage bar mounted upon said
carriage, a margin gage freely slideable upon
said bar, and coöperating means upon a
25 relatively fixed part disposed to contact
with a member carried by the gage to secure
the same upon said bar.

- 3 In a typewriter, a carriage provided
with a platen, a gage bar mounted upon said
30 carriage, a margin gage freely slideable upon
said bar, coöperating means upon a rela-
tively fixed part disposed to contact with a
member carried by the gage to effect a stop-
ping action upon said bar, and a device for
35 moving said coöperating means out of the
path of said gage.

- 4 In a typewriter, a carriage provided
with a platen, a gage bar mounted upon
said carriage, opposite margin gages freely
40 slideable upon said bar, coöperating stopping
devices for said gages, and means to co-
operate with either of said securing devices
for controlling the action thereof.

- 5 In a typewriter, a carriage provided
45 with a platen, a toothed gage bar mounted
upon said carriage, a margin gage freely
slideable upon said bar, a rocking member
mounted upon a relatively fixed part and
disposed to engage said bar, and means upon
50 the gage for moving said member into en-
gagement with a tooth of said bar.

- 6 In a typewriter, a carriage provided
with a platen, a toothed gage bar mounted
upon said carriage, opposite margin gages
55 freely slideable upon said bar, a rocking mem-
ber carried by a relatively fixed part, means
upon one gage for moving said member into
engagement with a tooth of said bar, a line
locking mechanism disposed to be actuated
60 by the opposite gage, and means upon said
member for releasing said line locking
mechanism.

- 7 In a typewriter, a carriage, a toothed
gage bar mounted thereon, opposite margin
65 gages freely slidably upon said bar, a rock-

ing member carried by a relatively fixed
part, means upon one gage for moving said
member into engagement with a tooth of
the bar, retaining means mounted upon the
opposite gage to engage the bar teeth, a co-
70 operating mechanism carried by a relatively
fixed part and disposed to actuate said re-
taining means, and means carried by the
rocking member for releasing said mechan-
ism from the retaining means.

8 In a typewriter, a carriage, a toothed
gage bar mounted thereon, a margin gage
freely slideable upon said bar, a rocking
member carried by a relatively fixed part
and having a tooth normally held out of en-
80 gagement with the bar, means upon the gage
for moving said tooth into engagement with
a tooth of the bar, and means for shifting
said rocking member out of the path of the
gage.

9 In a typewriter, a carriage frame, a
carriage mounted thereon, a gage bar upon
the carriage, a supporting member movably
mounted upon the frame, opposite margin
gages freely slideable upon said bar, a re-
90 taining device upon said member to coöper-
ate with one gage, locking means carried by
the opposite gage, a line locking mechanism
having a part disposed to actuate said lock-
ing means, and means upon the movable sup-
95 porting member for shifting said line lock
part and retaining device to release the line
locking mechanism and both of said gages.

10 In a typewriter, a carriage frame, a
carriage mounted therein, a gage bar upon
100 said carriage, opposite margin gages upon
said bar, retaining means upon one gage,
a line locking mechanism having a part dis-
posed to coöperate with said means, and a
device upon said frame arranged to contact
105 with the other gage and movable to release
said part of the line locking mechanism.

11 In a typewriter, a carriage frame, a
carriage mounted therein and provided with
a platen, a toothed gage bar upon said car-
riage, a rocking rod mounted upon the
frame, a margin gage freely slideable upon
110 said bar, a stop pawl pivoted upon said rod,
and means upon said gage for moving said
pawl into engagement with the teeth of said
bar.

12 In a typewriter, a carriage frame, a
carriage mounted therein and provided with
a platen, a toothed gage bar upon said car-
riage, a margin gage freely slideable upon
120 said bar, a rocking rod mounted upon the
frame, a stop pawl pivoted upon said rod,
and a depending toe from said gage dis-
posed to lift said pawl into engagement with
the teeth of said bar.

13 In a typewriter, a carriage frame, a
carriage mounted therein and provided with
a platen, a toothed gage bar upon said car-
riage, a margin gage freely slideable upon
130 said bar, a rocking rod mounted upon the

- frame, a stop pawl pivoted upon said rod and having a holding tooth, a spring carried by the rod and engaging said pawl, and a depending toe from said gage disposed to travel beneath the tooth of said pawl and raise the same into engagement with said bar.
14. In a typewriter, a carriage frame, a carriage mounted therein and provided with a platen, a toothed gage bar upon said carriage, a margin gage freely slidable upon said bar, a rocking rod mounted upon the frame, a stop pawl pivoted upon said rod and having a holding tooth, a spring carried by said rod and disposed beneath said pawl, a depending toe from said gage disposed to travel beneath the tooth of said pawl, an operating lever secured at one end of said rod, and a restoring spring secured to said rod and frame.
15. In a typewriter, a carriage frame, a carriage mounted therein and provided with a platen, a toothed gage bar upon said carriage, a margin gage freely slidable upon said bar, a rocking rod mounted upon the frame, a stop pawl pivoted upon said rod, means upon said gage for moving said pawl into engagement with said bar, a line locking mechanism, and an extension from said pawl disposed to engage a part of said mechanism for releasing the same.
16. In a typewriter, a carriage frame, a carriage mounted therein and provided with a platen, a toothed gage bar upon said carriage, a margin gage freely slidable on said bar, a pawl pivoted upon said gage and having a depending arm, means for normally retaining said pawl out of engagement with said bar, and means upon a relatively fixed part for actuating said arm.
17. In a typewriter, a carriage frame, a carriage mounted therein and provided with a platen, a toothed gage bar upon said carriage, a margin gage freely slidable on said bar, a pawl pivoted upon said gage and having opposite horizontal arms provided with means to engage the teeth of said bar, a spring disposed to retain said arms out of engagement with said bar, and means upon a relatively fixed part for actuating said pawl.
18. In a typewriter, a carriage frame, a carriage mounted therein and provided with a platen, a toothed gage bar upon said carriage, a margin gage freely slidable upon said bar, a pawl pivoted upon said gage and having opposite horizontal locking arms and a depending contact portion formed with an inclined return face, and a line locking mechanism having a pivoted contact member disposed to engage said portion and to be rocked by the return face thereof.
19. In a typewriter, a margin gage comprising a slide, a pawl pivoted thereon and having opposite horizontal locking arms and a depending contact portion formed with a lateral inclined return face, and a spring secured to the slide above said pawl to bear upon the opposite locking arms thereof.
20. In a typewriter, a carriage frame, a carriage mounted to reciprocate therein and provided with a platen, a gage bar upon said carriage having teeth upon its under face at one end and upon its upper face at the opposite end, margin gages freely slidable upon said bar, a stop pawl disposed to engage the teeth upon the under face of the bar and to engage the coöperating gage, a locking pawl upon an opposite gage disposed to engage the teeth upon the upper face of the bar, and means upon a relatively fixed part for controlling the action of one of said pawls.
21. In a typewriter, a carriage frame, a carriage mounted to reciprocate therein and provided with a platen, a gage bar upon said carriage having teeth upon its under face at one end and upon its upper face at the opposite end, margin gages freely slid- 90 able upon said bar, a rocking rod mounted in said frame, a carriage supporting wheel disposed to travel upon said rod, a stop pawl pivoted upon said rod to engage the teeth upon the under face of the bar and to engage the coöperating gage, a locking pawl upon the opposite gage disposed to engage the teeth upon the upper face of the bar and having a depending contact arm, means upon a relatively fixed part for engaging 100 said arm, and a tail from said stop pawl disposed to release said engaging means.
22. In a typewriter, a carriage frame provided with a gage bar, a margin gage freely slidable thereon, and a relatively fixed member disposed to engage and retain said gage upon said bar at the predetermined limit of the carriage travel.
23. In a typewriter, a carriage frame provided with a gage bar, a stop member adapted to engage said bar but normally out of the path thereof, and a margin gage freely slidable upon said bar and constructed to move said stop member into engagement therewith.

In testimony whereof I affix my signature.

CHARLES SPIRO.
